PROTECTIVE COVERING FOR DISPENSING
NOZZLES

Robert Hall, Los Angeles, Calif.

Application October 27, 1948, Serial No. 56,761

1 Claim. (Cl. 137—379)

1

My invention relates to means intended to provide a resilient protective covering for the hand operated valve structures of dispensing nozzles, particularly of gasoline or other pumps as used in gasoline stations and in other places, and in which the nozzle is inserted into a restricted filler opening after the cap covering such opening has been removed.

In using such dispensing nozzles the gasoline station attendant very frequently hits the edge of the filler opening and the adjacent fender in which the opening is usually mounted, and as a result thereof the finish of the automobile soon becomes marred about the gasoline filler opening by repeated blows from the metal trigger guards and nozzles of such gasoline dispensing means.

An object of my invention is to provide a novel device and covering of resilient material for dispensing valves and which device is of unitary construction and may be readily applied or removed from standard dispensing nozzles, but which nevertheless is securely retained in position on the dispensing nozzle.

Another object of my invention is to provide a novel cover for a gasoline dispensing nozzle and which cover is free of any metal clips, springs or other fittings, but which is held on the dispensing guard by the configuration of the molded cover.

A still further object of my invention is to provide a novel cover for guards of gasoline dispensing pump nozzles, and which cover is retained on the guard without additional means.

Other objects, advantages and features of invention may appear from the accompanying drawing, the subjoined detail description, and the appended claim.

The accompanying drawing illustrates the invention in a form I at present deem preferable.

Figure 1 is a side elevation of a typical gasoline dispensing nozzle, having my novel protective covering applied thereto.

Fig. 2 is a rear elevation looking in the direction of arrow 2, Fig. 1, and with parts broken away to contract the view.

Fig. 3 is longitudinal vertical section of my novel resilient guard cover as shown in Fig. 1, but on a larger scale, and detached from the dispensing nozzle.

Fig. 4 is an enlarged cross section on line 4—4, Fig. 1.

Fig. 5 is an enlarged cross section on line 5—5, Fig. 3.

In the drawing the numeral 10 indicates generally a guard for the trigger of a typical dispensing valve particularly used for dispensing

2

gasoline, and generally comprises a tubular spout S, spout connection SC, valve housing V in which flow controlling valve mechanism is contained and operated by depression of valve stem VS, an inlet connection I, and valve stem operating trigger T pivoted at Tp to a small bracket BR mounted on and projecting from spout connection SC. The structure so far described is that of a standard dispensing nozzle and except in combination with my invention forms no part thereof. It will be noted that heretofore when a gasoline station attendant carelessly pushed the spout S into an automobile gasoline tank opening (not shown) and which spout and guard 10 are not combined or provided with my invention, the guard 10 is often struck against the edge of the filler opening, and in certain types of automobiles where the opening of the gasoline tank is concealed under the fender or car body, the spout connection SC or guard 10 will strike against the car finish and scar the same, thereby making an unsightly appearance of the car's finish adjacent the filling opening for gasoline of such car. This is particularly annoying and obnoxious to new car owners, particularly of the more costly models, as well as to owners of other cars.

As shown in Fig. 2 the rear of the guard is bifurcated as at 99, the arms 10a, 10b of guard 10 being connected to an ear 12 depending from inlet connection I by a pin 14 passed through holes drilled through the upper ends of arms 10a, 10b and ear 12. The body 10c of the guard extends forwardly to the bracket BR.

My invention comprises providing a protective covering 50 for the nozzle or spout S and the trigger guard 10 of a usual gasoline dispensing outlet, and which covering is particularly disclosed in sectional views Figs. 3, 4 and 5; and generally comprises a gasoline and oil resistant flexible material that is combined with the associated with the spout S and trigger guard 10 to prevent the difficulties heretofore encountered by careless or negligent attendants dispensing gasoline or other fluids to receptacle openings around which are highly polished or glazed surfaces, that may be easily marred by impact therewith of a dispensing nozzle.

The protective covering 50 of my invention includes an enlarged bumper or stop portion 16 that has an opening 18 therethrough of a diameter to receive spout S, and be slid therealong until the shoulder 20 thereof is pressed against an abutment on the lower face of the spout con-

nection SC, and thereby arrests further upward movement of the stop portion 16 thereon.

Extending laterally from portion 16 of the protective covering and preferably integrally connected thereto a trough or channel-shaped section 22 is provided. The end of the channel-shaped section 22 adjacent the bumper portion 16 is shaped to fit over the lower face and edges of bracket BR, while the opposite end 49 of the section 22 fits closely around the knuckle at the lower end of the vertical bifurcated end formed by the arms 10a and 10b of the guard 10 and is continued therearound and upward sufficiently to overlie the opening between the arms 10a, 10b. At the point where the guard end 49 overlies the space between arms 10a, 10b the inner surface of the guard channel 22 is provided with an inwardly projecting stud 24, preferably molded integrally with the unitary guard protective covering and which is received in and engages in space 99. The length of the cover 50 is preferably slightly less than that of the guard 10 so that when the protective covering therefor is stretched and mounted in position the elasticity of the guard cover 50 will retain the same tightly in position on the guard, and the stud 24 will be retained in groove or space 99 to prevent the end 49 of protective guard from becoming disengaged from the bifurcated guard 10.

The underside 10c of the trigger guard 10 is usually provided with a rib 35, and the channel 36 of my protective guard 22 is provided with a groove 37 to receive the rib 35 and thereby, together with the upstanding arms 38 and 39 of the protective guard 22 and the tension exerted by the elasticity and pull of the end 49 against the end 10a and of the trigger guard, will serve to maintain my protective guard on the nozzle without extraneous means, so that my trigger guard may be sold as an independent unit for association and combination with standard gasoline dispensing nozzles now in use.

It will be evident that in use, since an attendant commonly slides the nozzle through the gas tank opening with the nozzle against the side of the opening, the bumper 16 will engage against the edge of the filler opening and stop further

inward movement of the spout and thus prevent the trigger guard from hitting against the edge of the opening or the adjacent fender, and if the attendant in manipulating the nozzle does hit the car body with the trigger guard adjacent the gas filling opening, the resiliency of the cover guard 50 will prevent any damage being done to the car finish adjacent such opening.

My invention particularly relates to the combination of my novel protective guard with a gasoline dispensing nozzle as above described and defined in the appended claim.

I claim:

The combination with a dispensing spout for fluids having a trigger guard associated therewith, and which trigger guard is bifurcated at the rear thereof; a unitary member having one end provided with an orifice to receive the dispensing spout thereof; a channel member extending from said spout receiving member and adapted to embrace the lower side of said trigger guard; said channel member being provided with an upturned end to embrace the rear of said trigger guard; and said upturned end being provided with a protuberance to be received between the bifurcated ends of said trigger guard; said channel member being held on said trigger guard by resiliency of said channel member along said trigger guard, and the engagement of said upturned end with the rear thereof.

ROBERT HALL.
